APPARATUS FOR EXPOSING AND DEVELOPING LIGHT SENSITIVE PHOTOGRAPHIC FILM

Roy E. Hurtig, Monte Sereno, Calif., assignor to Kalvar
Corporation, New Orleans, La., a corporation of
Louisiana

Filed Dec. 15, 1966, Ser. No. 5,053

Term of patent 14 years

(Cl. D61—1)

FIGURE 1 is a perspective view of the apparatus for exposing and developing light sensitive photographic film; and

FIGURE 2 is a plan view of the extreme top surface of said apparatus.

The left side of the apparatus, not shown, is essentially a mirror image of the right side seen in FIGURE 1. The bottom and rear side are essentially plain and unornamented.

I claim:

The ornamental design for an apparatus for exposing and developing light sensitive photographic film, substantially as shown and described.
